UNITED STATES PATENT OFFICE.

HERMAN HERMANSEN, OF BAYBRIDGE, OHIO, ASSIGNOR TO SANDUSKY PORTLAND CEMENT COMPANY, OF BAYBRIDGE, OHIO, A CORPORATION OF OHIO.

APPARATUS FOR DRYING FUEL.

1,173,510.

Specification of Letters Patent. Patented Feb. 29, 1916.

Application filed September 25, 1913. Serial No. 791,795.

To all whom it may concern:

Be it known that I, HERMAN HERMANSEN, a citizen of the United States, and resident of Baybridge, in the county of Erie, State of Ohio, have invented certain new and useful Improvements in Apparatus for Drying Fuel, of which the following is a specification.

This invention relates to an improved apparatus for drying coal or other fuel with arrangements for covering and utilizing the combustible dust ordinarily lost in fuel drying operations.

The novel features of the invention will be apparent from the following description, taken in connection with the accompanying drawings.

In the drawings, Figure 1 is a side view of an apparatus embodying my invention; and Fig. 2 is a similar view showing a slightly modified construction.

The drying of fuel is ordinarily carried on in revolving cylinders, heated either internally or externally. In this operation a considerable amount of dust is always formed by the agitation of the fuel. In case of internal firing there is some danger of explosion of this dust by contact with the fire gases, and the strong current of gases through the drier carries the dust into the atmosphere, causing loss and nuisance. This latter objection is also met with in the case of external heating, as it is necessary to provide for circulation of air through the drier to carry off the moisture evolved from the fuel, and this current of air also carries away a large amount of dust. It is also well known that external heating is very inefficient, being wasteful of heat. I have found it possible to overcome all these obstacles and to carry on the drying of fuel safely, economically, and without loss of dust, in an internally fired revolving drier, by (1) employing means to cool the fire-gases before they enter the drier to a point below the temperature of ignition of coal dust, by causing the fire-gases to pursue an elongated path and by mixing cool air with the gases, and (2) by drawing the dust-laden gases, as they escape from the drier, through a fan and forcing them into furnaces, where they serve the purpose for which an air blast is ordinarily employed, to atomize and diffuse additional fuel in pulverized form. In this way the dust car-

ried by the gases is burned and fully utilized, instead of being discharged as an objectionable effluent into the atmosphere. It is well known that in the ordinary process of coal dust burning in furnaces and kilns, as largely employed in manufacture of cement and other products, the air which is blown in with the fuel is only a small part of that required for combustion, the balance of the air required being drawn in by the stack draft through openings in the front of the furnace. The substitution of a blast of fire-gases containing more or less excess of air for the air blast commonly used, therefore, has no noticeable injurious effect upon the combustion in the furnace, while the heat of the gases and the combustible dust which they carry produces a marked economy in fuel used.

In Fig. 1 of the accompanying drawings, I have shown a revolving cylindrical drier 1, which communicates at one end with the combustion chamber 2 and which extends from a point near the top of that chamber at a slight angle downwardly. This cylindrical drier is mounted in any usual way on bearings 3 and is rotated by the gears 4 driven from any suitable source. Coal or other fuel is placed in the hopper 5 discharging into the screw conveyer 6 which carries the fuel across the upper part of the combustion chamber and discharges it into the end of the revolving drier 1. A small fire is maintained on the grate 7 air being admitted above the grate through the door 8 in regulated quantities and the fire-gases pass around the arches 9, 10, which serve to so lengthen the path of the gases that they are cooled to a point where they will not ignite the combustible dust in the cylinder 1. They will however be sufficiently hot to internally heat that cylinder and dry the fuel therein and it will be observed that in this form the gases move down the cylinder in the same direction as that followed by the coal or other fuel. The coal is discharged at the lower end of the cylinder through the outlet 11 and the fire-gases now carrying a considerable amount of dust picked up within the cylinder 1 pass to the stack 12 and if desired they may be allowed to escape from the top of that stack by opening the damper 13. In normal operation however the gases carrying the dust are drawn down through the pipe 14 by the fan

15 and are forced along a pipe 16 extending in front of the furnaces 17 and having branches discharging into those furnaces. The dust-laden gases discharged into the 5 furnace assists the combustion, and pulverized fuel contained in the hoppers 18 may be led down through the pipes 19 so as to be discharged into the furnace with and by means of the blast of gas and dust, any 10 suitable form of burner being used for the purpose. I have shown diagrammatically a feeding device 20 at the bottom of the hoppers 18. In this construction the dust-laden gases take the place of the ordinary 15 air blast used for burning pulverized fuel. While I prefer to use the stack 12 with its outlet valve 13, it will be understood that this is not necessary but that the gases may be conveyed directly by means of the fan to the furnace. This stack serves a useful purpose in case of interruption to the operation 20 of the furnace or the fan, being used at that time as a convenient exit for the gases.

In Fig. 2 I have shown a construction 25 similar to that illustrated in Fig. 1 except that the revolving cylinder 1 is inclined upwardly from the combustion chamber 2 and the fuel is fed into it at the opposite end and is discharged at the end next to the 30 combustion chamber. In this case the screw-conveyer 21 which receives the fuel from the hopper 5 leads into the elbow at the bottom of the stack 12 and consequently the coal passes down the cylinder 1 to the 35 discharge outlet 22 while the fire-gases from the combustion chamber pass up along the cylinder in the opposite direction from the movement of the fuel. The construction of the parts for utilizing the dust-laden gases 40 in the furnaces is the same as that shown in Fig. 1.

Having thus described my invention, what I claim is:

1. A fuel drier consisting of an internally 45 heated revolving cylinder, an exit pipe, exhaust fan and delivery pipe for conveying dust-laden gases from drier to furnaces, and means for supplying pulverized fuel to the gases as they enter the furnaces, all sub- 50 stantially as shown and described.

2. A fuel drier consisting of an internally 55 heated revolving cylinder, means for feeding raw fuel to drier, an exit pipe, exhaust fan and delivery pipe for conveying dust-laden gases from drier to furnaces, and means for supplying pulverized fuel to the gases as they enter the furnaces, all sub- 60 stantially as shown and described.

3. A fuel drier consisting of an internally 65 heated revolving cylinder, means for feed-

ing raw fuel to drier, a fire-place for heating drier, an exit pipe, exhaust fan and delivery pipe for conveying dust-laden gases from drier to furnaces, and means for supplying pulverized fuel to the gases as they 65 enter the furnaces, all substantially as shown and described.

4. A fuel drier consisting of an internally heated revolving cylinder, means for feeding raw fuel to drier, a fire-place for heating drier, arches in fire-place to cause products of combustion to traverse an elongated path, an exit pipe, exhaust fan and delivery pipe for conveying dust-laden gases from drier to furnaces, and means for supplying 70 pulverized fuel to the gases as they enter the furnaces, all substantially as shown and described.

5. A fuel drier consisting of an internally heated revolving cylinder, means for feeding raw fuel to drier, a fire-place for heating drier, arches in fire-place to cause products of combustion to traverse an elongated path, openings in fire-place to admit additional air to the products of combustion, an 80 exit pipe, exhaust fan and delivery pipe for conveying dust-laden gases from drier to furnaces, and means for supplying pulverized fuel to the gases as they enter the furnaces, all substantially as shown and de- 85 scribed.

6. In an apparatus of the class described, the combination of an inclined rotatably mounted cylinder, means for feeding raw fuel to said cylinder, a combustion chamber 95 connected with one end of said cylinder, a fire-place in said chamber, arches in said chamber between said cylinder and fire-place to cause products of combustion to trans- 100 verse an elongated path, the wall of said combustion chamber having an opening therein between said arches and the fire- place to admit additional air to the products of combustion, an outlet at the lower end of the cylinder, a stack at the end of the 105 cylinder opposite the combustion chamber, a damper controlling the flow of gas through said stack, a furnace, an exhaust fan for withdrawing dust laden gas from said stack and delivering the same to said furnace, and 110 means for supplying pulverized fuel to the gases as they enter the furnace, substantially as shown and described.

In testimony whereof I affix my signature in presence of two witnesses.

HERMAN HERMANSEN.
